UNITED STATES PATENT OFFICE.

FRANK L. LOOK, OF LAMANDA PARK, CALIFORNIA.

DESIGN FOR A BEVERAGE COOLER.

Application filed February 8, 1928. Serial No. 25,280. Term of patent 3½ years.

To all whom it may concern:

Be it known that I, FRANK L. LOOK, a citizen of the United States, residing at Lamanda Park, in the county of Los Angeles, State of California, have invented a new, original, and ornamental Design for Beverage Coolers, of which the following is a specification, reference being had to the accompanying drawing, forming part thereof.

The figure is a side perspective view of a beverage cooler, showing my new design.

I claim:

The ornamental design for a beverage cooler as shown.

FRANK L. LOOK.
